Atty.

UNITED STATES PATENT OFFICE

2,156,092

SHED-FORMING DEVICE

Andrew Johnson, Chicago, Ill.

Substituted for abandoned application Serial No. 95,105, August 10, 1936. This application November 22, 1938, Serial No. 241,857

4 Claims. (CL. 139—33)

This invention relates to a device for forming a shed to facilitate the stringing of instruments used in sports. When tennis rackets or other similar instruments are strung or restrung by hand the transverse strings are threaded through alternate warp which are in substantially the same plane and under great tension so that as the weft strings are drawn through for the full length, they will, as it were, saw on the warp or longitudinal strings and injure them. Furthermore, a great deal of time is lost by such tedious methods.

An object of the present invention is the provision of a device which is adapted to be applied rapidly to the warp strings of a tennis racket or other similar device for forcing alternate threads or strings in opposite directions to form a shed whereby a needle or sheddles may be passed through the shed carrying a transverse string easily and rapidly therethrough.

Another object of the invention is the provision of a simple and efficient device which may be readily applied to the warp strings of a tennis racket or other similar bat used in sports for forming a shed through which is adapted to be inserted a transverse string, the device being adapted to be rocked for not only spreading alternate strings from the remaining strings but for rocking the device to an operative position.

A further object of the invention is the provision of a device for forming a shed of warp strings of a tennis racket or similar bat used in sports to facilitate the threading of transverse strings, the device having means for guiding spaced tongues or abutments into proper engagement with alternate strings so that when the device is rocked from an initial to an operative position, two series of alternate strings will not only be held in spaced relation but the device will be retained in the operative position by the warp strings which are under great tension.

This invention will be best understood from a consideration of the following detailed description, in view of the accompanying drawing forming a part of the specification; nevertheless, it is to be understood that the invention is not confined to the disclosure, being susceptible of such changes and modifications which shall define no material departure from the salient features of the invention as expressed in the appended claims.

In the drawing:

Figure 1 is a plan view of a tennis racket showing my device in an operative position.

Figure 2 is a fragmentary side view in elevation of the device.

Figure 3 is a longitudinal side view in elevation of the device, showing a face which is opposite to that disclosed in Fig. 2.

Figure 4 is a fragmentary edge view of the device.

Figure 5 is a transverse section of the device shown applied in its initial position to the warp strings of a tennis racket.

Figure 6 is a transverse section showing a view similar to that of Fig. 5 with the device moved to an operative position between the warp strings of a tennis racket.

Figure 7 is a view in perspective of one form of 15 needle for drawing the transverse strings through the shed of the warp strings.

Referring more particularly to the drawing, 10 designates the frame of a tennis racket which is adapted to be restrung and showing warp strings 11 in position. These strings have been threaded through the usual perforations formed in the frame and have been placed under a great tension so that the racket is now in condition for the application of weft strings 12. It will be appreciated that the stringing of the racket or frame with the warp strings 11 is a comparatively simple matter but the application of the weft strings 12 presents a complicated problem due to the fact that these strings must be inserted through 20 alternate warp strings at one face while engaging the opposite faces of the remaining strings.

When the transverse string 12 is threaded through the longitudinal strings 11 it will be found that the transverse string must be inserted 35 through a pair of the longitudinal strings in one direction and then inserted in the opposite direction through the next pair which includes one of the strings of the first pair. When the string has been inserted through the last of the pair of longitudinal strings the entire weft string must be drawn through the longitudinal strings for substantially its full length and the weft string is of considerable length. When this threading and drawing takes place a number of times the trans- 40 verse string becomes greatly worn and it may be necessary to either apply a new section or to remove the entire work which has been done. In other words, when the weft string is drawn through the longitudinal strings 11 which are in 50 the same plane, there is a constant sawing action taking place not only on the string which is being drawn through but on the longitudinal strings which are under great tension.

The device which constitutes the subject-mat- 55

ter of the present invention is intended to form a shed 13 (Fig. 6) of the various longitudinal strings so that the transverse strings 12 may be inserted through the shed and thereby eliminate the sawing action previously explained.

5 The shed forming device 14 is in the shape of an elongated member which is substantially flat and relatively narrow and formed of any suitable material such as metal or composition material. It 10 will be noted that the outer ends as shown at 15 are rounded so that when the device is rocked these rounded ends may be moved in close association with the curved restricted portions 16 of the frame 10 so that these rounded portions 15 will clear the curved portions of the frame.

15 The bar 14 is provided along one edge with a plurality of spaced notches 20 thereby forming fingers 21. The outer ends of these fingers, as shown at 22, are adapted to engage or be seated 20 upon the longitudinal strings 11 as will be presently explained. One side wall 23 is substantially straight with the upper end of the wall merging into a curved portion 24 and this curved portion is continued in a downwardly extending curved 25 edge 25. The material of the bar adjacent each notch is provided with a cutaway section 26 at the inner face of the bar to form a flared portion to permit the string 11 to move freely in the notch.

30 A lip 30 extends laterally from the lower end of a rib 31 and substantially across the notch 20 with the free end 32 of the lip terminating short of the curved side wall 25 of each notch. Referring more particularly to Figs. 5 and 6 it will be seen that each lip has a rounded surface 33 which moves in engagement with the underface of a longitudinal string 11 when the bar 14 is rocked from the initial position in Fig. 5 to its operative position Fig. 6. This rounded portion of the lip which moves over the underface of the string 11 prevents wearing of the string during this slight angular rocking movement of the bar. The free end 22 of the finger 21 is also rounded as shown in Fig. 6 since it moves over the opposite face of an alternate string 11A and thus 45 prevents any wearing action on the string.

The ribs 31 increase in thickness from their upper ends 34 to a point where they merge into the lips 30 and these ribs have one edge substantially in alignment with the wall 23 of each notch. 50 20. Since these ribs increase in thickness they are gradually raised from the plane of the bar 14 to a plane which is located outwardly of one face of the bar so that the lips 32 which extend laterally from such ends of the ribs will also be located within a plane which is parallel to a face of the bar.

55 As has been explained, the lips 30 and the ribs 31 project beyond the surface of the bar 14 so that when said surface of the bar is placed in engagement with the longitudinal strings 11 as shown in Fig. 5, the lips being in a plane outwardly of said surface, will pass through the spaces between the strings 11 whereby when the bar is shifted slightly to the left in Fig. 1 the series of lips will engage beneath alternate strings 11 of the racket while the fingers 21 will be located above the plane of the longitudinal strings 11.

60 It is only necessary to rock the bar 14 from the position shown in Fig. 5 to the position shown in Fig. 6 when the free ends 22 of the fingers 21 will engage alternate strings 11A and the lips 30 will engage the adjacent faces of the remaining strings 11 and these two series of strings will be 70 forced apart to form the shed 13 (Fig. 6) and the

bar will be retained in a substantially locked position by the tension of the strings 11 and 11A because said bar has been rocked to a position beyond dead center of the contact of the strings 11 and 11A with the lips 30 and the fingers 21.

5 The transverse or weft strings 12 may be inserted through the shed 13 with facility and this insertion is aided by means of one form of needle illustrated in Fig. 7. This needle comprises a shank 40 formed of resilient wire which adjacent 10 its end is formed into a coil 41 and beyond this point the wire is twisted into a pair of jaws 42 and 43 which by reason of the resiliency of the wire is adapted to clamp or grip the free end 12A of the weft string 12 with sufficient force to permit the operator to draw the needle through the shed 13 and likewise the string 13. The coil 41 forms a protective cylinder for the extreme outer end of the weft string 12 so that this free end will not project beyond the needle and engage the 20 longitudinal strings 11 and obstruct the free movement of the needle.

25 After the shed 13 has been formed, as shown in Fig. 6, the needle is inserted through the shed from one side of the racket to the other and the free end of the weft string 12 is inserted between the jaws 42 and 43 of the needle and seated within the coil 41 so that when the shank 40 is withdrawn by means of the finger-piece 44 the string 12 will be drawn through the shed. Sufficient 30 pull is applied to the string 12 after the same is in position and the bar 14 is moved to the inoperative position shown in Fig. 5 and then removed. The tension of the longitudinal strings 11 will hold the weft string 12 in position and the 35 bar is then moved to another position so that the lips 30 will engage beneath the series of strings which had been previously engaged by the fingers 21 and said fingers will be seated or engage the other series of strings which had been previously 40 engaged by the lips 30. When the bar is rocked to position shown in Fig. 6 the shed will be formed again but with the series of strings forced apart in a reverse manner. This method is continued until the frame has been restrung.

45 It will be appreciated that various lengths of the bar may be forced for various sizes of rackets and several lengths of these bars may be used for forming the sheds adjacent the opposite ends of the racket frame and for the central portion of 50 the frame.

This application is a substitute for the abandoned application Serial No. 95,105, filed Aug. 10, 1936.

55 I claim:

1. A device of the class described comprising an elongated member having spaced depending fingers located substantially in the plane of said member, and a lip projecting from each finger across the space between a pair of fingers, said 60 lips being located substantially in a plane which is offset from the plane of said member, the free end of each lip terminating short of the adjacent- 65 ly disposed finger.

2. A device of the class described comprising an elongated member having spaced depending fingers, a lip projecting laterally from each finger and across the space between a pair of fingers, said lips being offset from the plane of the fingers and inwardly of the free ends of said fingers. 70

3. A device of the class described comprising an elongated member having spaced depending fingers, a lip projecting laterally from each finger and across the space between a pair of fingers, said lips being offset from the plane of the fin- 75

gers and inwardly of the free ends of said fingers, a rib disposed adjacent each finger and transversely of the member for guiding the lips and free ends of the finger into engagement with spaced longitudinal strings of a racket.

4. A device for forming a shed of the strings of a tennis racket comprising a substantially rigid member having spaced transverse ribs on one face and a lip projecting laterally from each rib, said member adjacent the lips being provided with notches thereby forming spaced fingers, the

5 lips extending across the notches and having free ends terminating short of an adjacent wall of the notch so that alternate strings may pass beyond the free end of a lip and be supported by the lips with the fingers engaging the remaining strings when said member is lying in flat contact with the strings, the member when rocked through a predetermined angular position causing the lips and fingers to force the two groups apart.
